US0D1058147S

(12) United States Design Patent (10) Patent No.: US D1,058,147 S
(45) Date of Patent: * Jan. 21, 2025

(54) TOTE

(71) Applicants: Crocs, Inc., Broomfield, CO (US);
Balenciaga, Paris (FR)

(72) Inventor: Demna Gvasalia, Paris (FR)

(73) Assignees: Crocs, Inc., Broomfield, CO (US);
Balenciaga, Paris (FR)

() Term: 15 Years

(21) Appl. No.: 29/815,163

(22) Filed: Nov. 11, 2021

(51) LOC (15) Cl. 03-01

(52) U.S. Cl.

USPC D3/246
